UNITED STATES PATENT OFFICE.

HOWARD B. RAND, OF MERRIMAC, MASSACHUSETTS.

ELECTRIC INCANDESCENT LAMP.

1,275,305.

Specification of Letters Patent. Patented Aug. 13, 1918.

Application filed December 18, 1917. Serial No. 207,784.

To all whom it may concern:

Be it known that I, HOWARD B. RAND, a citizen of the United States, residing at Merrimac, in the county of Essex and State 5 of Massachusetts, have invented new and useful Improvements in Electric Incandescent Lamps, of which the following is a specification.

This invention is embodied in certain 10 improvements hereinafter described and claimed whereby the neck or base of an incandescent lamp may be readily converted from a double to a single contact base, and from a single to a double contact base, without change in the number of component 15 parts.

Of the accompanying drawings forming a part of this specification,

Figure 1 is a view showing in elevation 20 the bulb, the leading-in wires, and the incandescent filament of an incandescent lamp, and in section the neck or base of the lamp, the conducting members hereinafter described being adjusted to form a two- 25 contact base.

Fig. 2 is a view similar to Fig. 1, showing the conducting members adjusted to form a single contact base.

The same reference characters indicate the 30 same parts in all of the figures.

In the drawings, 12 represents the bulb of an incandescent lamp, 13, 13 the leading-in wires, and 14 the incandescent filament supported by said wires.

35 The neck or base of the lamp includes a body 15, of any suitable insulating material, in which portions of the leading-in wires are embedded, and a sleeve 16, of conducting metal, embracing the body 15, the outer 40 end of the body being exposed at the outer end of the sleeve.

The bulb and neck may be connected by any suitable means, which may include the usual glass nipple 17, through which the 45 leading-in wires extend.

In carrying out my invention I connect with the outer portions of the leading-in wires two conducting members 19 and 20, which may be made of any conducting metal 50 or metallic material that is capable when formed into a strip, of being bent to cause its outer portions to project in different directions, the ductility of the material of the said members being such that the members 55 are not liable to be broken or injured by one or more bendings. The inner portions of

said members are embedded in the body 15, and the outer portions project from the outer end of said body. I prefer to locate the embedded portion of the member 19 60 relatively near the center of the body, and the corresponding portion of the member 20 relatively near one side of the periphery of the body, the leading-in wire connected with the member 20 being preferably offset with- 65 in the body, as shown by the drawings.

Referring to Fig. 1, it will be seen that the outer portions of the members 19 and 20 are both bent in the same direction, and are located in position to form two contact 70 terminals, both insulated from the sleeve and located in position to engage two contact terminals in a lamp socket formed to receive the lamp base or neck.

To convert the base or neck into a single 75 contact base, I bend the projecting portions of the members 19 and 20 in a different direction, as indicated by Fig. 2. In doing this, I displace the member 20 into short-circuiting engagement with the sleeve 16, 80 said sleeve and the corresponding portion of the body 15 being preferably provided with a recess 21 formed to receive the displaced portion of the member 20, so that the outer side of said displaced portion is sub- 85 stantially flush with the periphery of the sleeve. The bending of the member 19 is such that said member is located in position to form a single central contact terminal, insulated from the sleeve and adapted to 90 engage a single contact terminal in a lamp socket.

The member 19 may be formed to constitute either a single terminal, or a member of a double contact terminal, without the operation of bending it. It is essential, however, that the member 20 be displaced or bent to locate it in short-circuiting engagement with the sleeve 16. 95

I claim:

1. An electric incandescent lamp interchangeable from double to single contact and vice versa, comprising a bulb, a base attached thereto, and composed of an insulating body and a conducting sleeve embracing the body, the outer end of the body being exposed at the outer end of the sleeve, leading-in wires partially embedded in the body and supporting an incandescent filament, and conducting members connected 105 with the leading-in wires and projecting from the outer end of the body, the project- 110

ing portions of said members being adapted to simultaneously form two contact terminals, both insulated from the sleeve, one of said members being flexible and adjustable to form either a contact terminal insulated from the sleeve and adapted to engage a contact terminal in a lamp socket, or a short-circuiting connection with said sleeve, and the other member being adapted to form at the same time a contact terminal insulated from the sleeve and adapted to engage a contact terminal in a lamp socket.

2. An electric incandescent lamp interchangeable from double to single contact and vice versa, comprising a bulb, a base attached thereto, and composed of an insulating body and a conducting sleeve embracing the body, the outer end of the body being exposed at the outer end of the sleeve, leading-in wires partially embedded in the body

and supporting an incandescent filament, and flexible conducting members connected with the leading-in wires and projecting from the outer end of the body, the projecting portions of said members being adapted to be bent in one direction to simultaneously form two contact terminals, both insulated from the sleeve and located in position to engage two contact terminals in a lamp socket, and to be bent in a different direction to displace one member into short-circuiting connection with said sleeve, and locate the other member in position to form a single central contact terminal insulated from the sleeve and adapted to engage a single contact terminal in a lamp socket.

In testimony whereof I have affixed my signature.

HOWARD B. RAND.
